ACCOUNTING, CHECKING, AND PUNCH-RECORDING SYSTEM

John P. Buckley, Washington, D. C.

Application June 28, 1937, Serial No. 150,857

29 Claims. (Cl. 178—3)

This invention relates to an apparatus whereby desired information may be obtained from a remote point with a minimum loss of time and consists of a dialing station from which impulses 5 may be electrically transmitted to a central office wherein is housed certain apparatus for automatically imparting desired information through a signal light which will indicate the customer's standing by dialing his credit number.

Another object of the invention is to provide an apparatus of this character including a dialing system at the sending station having printing means associated therewith for printing symbols 15 in blank spaces provided upon a sales slip or voucher and also means for transmitting electrical impulses over a circuit to the office where mechanism will be actuated to punch a card and print corresponding symbols simultaneously upon 20 the card, whereby a duplicate record of the sale transaction may be made and reserved.

Another object of the invention is to insure positive identification of the customer by requiring his signature on a perforated card. When 25 the card is presented for making a purchase not only is the dialing monitored in accordance with the customer's number but also the identity may be verified by having the customer sign the voucher.

Another object of the invention is to so construct the apparatus that while the sending mechanism will be manually operated from a dial, resembling a dial such as provided upon automatic telephone system, the mechanism at 35 the remote office will selectively adopt a customer's credit number upon a wired board which, after dialing the last digit, signals back on pressing a button, to the sales person a complete understanding of the customer's status.

Another object of the invention is to create a 40 dialing system composed of dialing units so connected with each other with respect to a small group of two-motion switches, selectively wired, in the remote station, that any one of the group 45 of dialing units may solely select the two-motion switches without the interference of any one of the other dialing units.

The invention is illustrated in the accompanying drawings, wherein:

Figure 1 is a top plan view of the sending apparatus.

Figure 2 is a sectional view, taken vertically through the sending apparatus.

Figure 2a is a fragmentary view of a projecting arm from the dial shaft.

Figure 3 is a fragmentary elevation view of the record board.

Figure 4 is a plan view of the punch-print mechanism.

Figure 5 is a side elevation view of Fig. 4.

Figure 6 is a view showing the front end of the punch print apparatus; the table top is shown in section.

Figure 7 is a fragmentary sectional view of the bars composing the punching unit, as through 10 the line, a—a of Fig. 4.

Figure 8 is a view of the striking arm associated with the solenoid printing and tripping means.

Figure 9 is a diagram showing connection of 15 the dialing units and their connections, together with the two-motion switches in the remote station and the record board.

The numeral 1 designates the case having the usual six sides to make up a box. Five of the 20 sides composing the front 2, rear 2', bottom 3, top 4, side 4' are shown in Fig. 2 with the side omitted for a view of the several parts of the mechanism inside the case. Depending from the top and fixed thereto are the straps 5 and 6 which, 25 as shown, support the solenoid 7, having an armature 8, the forward end of which is provided with the slot 9, in which the upper part of the trigger 10 is housed and is drawn backward by the pin 11, when the armature is retracted. The 30 bottom portion of the trigger has the forked end 12 so shaped to engage the pin 13, through upright rod 14, journalled in bearing 15, and supported by the arm 16, attached to the strap 6 of the solenoid. The upper end of the rod 14 is provided with the striker 17, which, when the solenoid is energized, strikes upwardly and, in engaging the voucher 17', inked ribbon 18' strikes against one of the symbols 44 of the dialing mechanism to form an impression of the symbol 40 or the face of the voucher. The ribbon is actuated in a step-by-step motion for presenting a fresh portion of the ribbon to the striker by the cam 19', which is fixed on the shaft 42, to engage the arm 20' pivoted on the standard 21', leading 45 out from the casing. The lower portion of the shaft 20' loosely engages the driving rod 22' slidably bearing in the standard projection 23' while the outer end extends beyond the fixed pawl 24' to journal in the projection 25' extending 50 from the casing.

The ribbon mechanism just described and the dialing and card checking mechanism herein-after described are housed and supported by the upper case 304. At the lower outer edge of the 55

case is the hinge bracket 386, the latter being pivoted, see Fig. 2, to the hinge bracket 387 provided at the upper outer edge of lower case 4. The rear portion of the bottom of the case 304 5 extends outwardly, upwardly and inwardly, to the case in order to support, with the aid of the insulation bracket 385, the plate 62.

The spring depressed pawl 24' engages the ratchet 26' which is fixed on the shaft 27' carrying the ribbon spools 28'. The guide rollers 10 29' serve to level the inked ribbon beneath the symbols on the typewheel. The outer end of the armature 8 has the flange 18, which serves as a tripper for the spring depressed escapement 19, held fast on the depending shaft 20 which is journaled in bearing 21, attached to the case. At the bottom of the shaft 20 is shown the rockable arm 22 (Fig. 1) which is pivoted as at 23, on the projecting angle 24 fixed to the shaft 20. 15 The rockable arm 22 is for the purpose of allowing the flange 18 to pass inwardly without disturbing the escapement as when the solenoid becomes energized; in this case the rear of the arm 22 rises above the pin 25 on the angle 24. The reverse movement of the armature, however, as 20 when the solenoid is deenergized and the spiral spring 26 forces the armature outward, to cause the flange to depress the arm against pin 25, when the whole becomes an integral part to move the escapement 19 by one step-up motion.

The spring 26' depresses the forward end of the escapement in mesh with the ratchet teeth 27, cut in the side of the bar 28, which also carries the rackbar 29, beneath its surface. The bar 28 35 is provided at one end with the handle 30, and is free to slide in the groove 31 of the top of the case. Extending outwardly from the bar 28 and attached thereto is the arm 328 which has at its outer end upwardly extending portions 329 and 40 330. At the top of extension 330 is provided a conventional clamp 331 adapted to receive the customer's card 61. The bar 28 is also normally tensioned backwardly under control of the escapement through the spiral spring 32, one end 45 of which is anchored to bearing 33, while the other end, surrounding the shaft 34, is attached to the gear 35. The shaft is revolvably supported by the bearing 33 and 37. The bar is also provided with the spring clip 38, through which 50 means the voucher is clamped in proper position for printing and thereafter, with each electrical impulse from the movable stop 40 to the solenoid 7, becomes a part of the step-by-step movement of the bar until all of the columns have 55 been printed on the voucher, when the bar will have come to rest at its farthest backward movement. The insulation strip 28'' fixed to the side of the bar engages the insulated brush 28''' after the credit number has been dialed and 60 serves to break the current through the two-motion switches at a time when only printing of the voucher and punching of the card is wanted. The insulated brush is shown, note Fig. 9, electrically contacting with the metallic portion of 65 the bar, which in contacting with the wall 4' of the case 4, forms a portion of the ground system 213 which may be controlled by the switch 219.

The finger plate 40', in this particular case, has the usual ten openings 41 and is rigidly supported 70 on the shaft 42, which extends downward to the disc 43, carrying the symbols 44, which, as a group, represents similar symbols, as might be visible through the openings 41, printed on top of the plate 45 of the case 45'. The two sets of 75 symbols 44 and 45 are therefore synchronized.

although they may not be in true alignment with respect to their starting point. The movable finger stop 40 is resiliently held forward by the spring 47, surrounding the shaft 48, which is suitably journaled to the side of the case. Extending therefrom and forming a part of the shaft 48 is the projecting arm 49 which is made to force the two blades of the switch 39 into electrical contact, when the movable finger stop is engaged.

Progressively downward on the shaft 42, and meshing with the teeth 50 of the bar 51, journaled in the bearing 52 and side of frame 53, is the gear 54, at the end of the bar is the hinge 55, which flexibly supports the spring depressed contact arm 56, having a metallic ball 57, held loosely and made captive by several crowfeet 58, for the purpose that, when the customer's punched card 59, identifying his credit number 60, previously punched in accepting the card, is introduced into the grooves 333 and 334 on the table 62 and clamped at 331 and is thus properly aligned with the travel of arm 56 and arranged to be advanced step-by-step with the voucher as each digit of the customer's number is dialed. 20 As the proper digits are dialed the contact ball 57 will successively make electrical contact with the plate 62 through the holes in the customer's card. This action in each instance completes a circuit through the solenoid 7 and the magnet 30 65, which circuit may be traced by the source 66 (Fig. 9) and from the negative side of source by conductor 67, bar 51, ball 57, table 62, conductor 71, through the finger stop switch 39, thence through conductor 73 to solenoid 7 and through conductor 74 to magnet 65 and by conductor 75 to the positive side of source.

The circuit, when energized by the metallic ball 40 electrically contacting with the table through the hole in the card, through magnet 65, controls the pawl 78, which is pivoted as at 79, on the extending arm 80 attached to the case. The spring 81 normally holds the pawl in mesh with the ratchet teeth 82 of the bar and prevents a reverse movement of the bar unless the magnet 65 is 45 energized. At this instant the magnet attracts the armature 83, pivoted at the lower end and loosely connected with the link 84, which loosely connects with the top end of the pawl, and when forced onward disengages the lower end of the 50 pawl from the teeth of the bar. Should an error occur in dialing a number and the number be less in value than the right number to be dialed, the finger plate need only to be turned further on until the ball contacts with the table through 55 one of the holes in the card when the magnet 65 will become energized to release the pawl 78. When released the spiral spring 85 (Fig. 2) surrounding the shaft 42 with one end fastened to the bearing 86 and the other end fixed to the 60 shaft 42, unwinds, and in reversing the dial movement, causes the insulation cam 87, made fast on shaft 88, to open and close the switch 89 alternately until the dial movement comes to rest.

But should the dialed number be of greater value than the number wanted the release of the pawl 78 must come through pushing the button 90, held normally outward by spring 91, in bearing 92. The extending rod 93 of the button 70 bears on the armature, and when moved forward releases the pawl 78, as the magnet would do when energized to restore the dialing system to zero. At this point it must be noted that through the sleeve member 94 on the rod, the current 75

energizing the two-motion switches 102, magnets 146 and 152 is automatically broken as it moves away from the brushes 95 and 126, immediately before the pawl 18 is released or before the switch 89 is actuated. In this way the whole is restored to zero without effecting any part of the recording system. The dash pot 96 is designed to delay the return stroke of the armature and after button slightly until the dialing system is restored to zero, when, on releasing the button, the sleeve 94 will again short the brushes 95 and 126. Tracing the circuit to the remote station from the dial switch 89, are conductor 97, normally open button switch 100, signal lamps 98 and 99, thence through normally closed button switch 100' connected in series, through conductor 101 to the insulated brush 28''' metallic portion of the bar 28''', wall 4' and ground 213, thence to the two-motion switches 102 by conductor 101', in the remote station, where the conductors 103 from the selector 104 of the two-motion switches are wired to their respective sockets 105 on the insulation frame 106. Connected to each socket is a resistance coil 107 which is made to extend over to the companion socket 108. Beyond the sockets 108 are the credit account numbers 109 and adjacent thereto are cards 110 bearing the customer's name and address.

The common, or negative wire 111 leading from the selector has the individual leads 112 (Fig. 3) which are provided with the plugs 113, designed to plug into the sockets either side of the resistance coil 107 as shown. The conductor 111 continues through the two-motion switches to the conductor 115 to the positive side of the source 116, and from the negative side of source by the conductor 117, and connecting thereto is the conductor 118, which leads to the brush 119, normally disconnected from the sleeve 120, on rod 121, fixed to the button 122. The spring 123, Fig. 1, presses the button outwardly. Leading from the brush 124 the conductor 125, continues to the brush 95, thence to the sleeve 94, to brush 126, and returning to the switch 89 by conductor 127. This circuit, thus described, electrically controlling the signal lights, two-motion switches and card puncher, is normally open at two points of the circuit, switch 89 and button switch 122. The switch 89 forms a part of the dialling system and is alternately controlled by the cam 87, Fig. 1, as during the impulsive time or during the time when the finger plate, under pressure of the spiral spring 85, returns to zero.

The button switch 122 normally closes the dial locking circuit for controlling the movement of the dialing mechanism of each unit, which circuit is composed of the brush 128, metallic sleeve 129, brush 130, conductor 131, brush 129', sleeve 129'', brush 130', conductor 132, source 133, conductor 134, magnet 135, conductor 136, magnet 137, conductor 138 and back to the brush 128. This circuit is for the purpose of keeping the armatures 139 away from the recess 141, which is peripherally provided on the type wheel 43 and is also the means for releasing the button by being positioned low enough to permit the sleeve 129 to freely pass the angle 144 of the extending arm 142 when the button is actuated. It will therefore be seen that if the button 122 is pushed and held into position to electrically engage the two-motion switches in the central office, such action will automatically render all other dialing unit inactive, as shown in "No. 1" by dotted lines where the button has been

pressed, and in "No. 2" by solid lines, where the locking circuit has been broken.

During the time of the engagement with the two-motion switches the signal lamps 131' of the locking circuit remain dark and flash up when the circuit is restored as a signal to indicate that the central office is disengaged. Independently of this signal, however, as mentioned, all other units would be found inoperative should any attempt be made to dial a credit number.

In pressing the button the locking circuit is not broken until after the sleeve 129 has slightly passed the angle 144, when thereafter the angle is held downward by the sleeve to avoid locking as it would otherwise do, as shown in "No. 2", 15 when the armature spring 143 pulls the armature backward to engage the type wheel 43. The angle 144' of the arm 142' of course rises up correspondingly before the sleeve 129' and in this way prevents the button from being pressed inwardly, so that neither the finger plate nor the button may be operated to disturb the circuits of the system during time of engagement with the record board.

Many dialing units may form a part of the 25 dialing system since it takes but two and one-half seconds to dial a number and receive an approval or disapproval of a customer's credit account. The return signal, after the dialing has selectively engaged the right resistance coil 107 30 on the board 106, otherwise identified by the name, number 109, signals back, the kind of signal, on pressing the button 100, according to the position of the plug and socket engagement, as for instance, if the plug 113 engages the socket 35 105, the resistance 107 in the circuit is shunted. In this case the current is strong enough to energize the two green lamps 98, 99, which will indicate to the salesperson that the account is disapproved. All disapprovals cause the bell 105' 40 to ring which may be followed up by an explanation over a phone by the attendant of the board to the salesperson.

If only one green light flares up after the dialing, as when the plug engages the socket 108, the 45 resistance is thrown in the circuit to reduce the voltage down to where the low resistance lamp 98 will burn only; this will indicate that the account is approved.

It must be noted that whatever electrical impulses are imparted to the two-motion switches the same number of impulses when the switch 154 is closed are also given to the card puncher or through the magnet 152 which is connected to the trunk lines 101 and 115 by the leads 156 and 153, 55 156 and switch 154. The solenoid 146 cooperating with the impulse magnet 152 of the card puncher is connected to the dialing switch 145 and is operated by the projecting finger 42' (Fig. 2a) fixed to the shaft 42 at a predetermined time, between 60 the last impulse and where the dial comes to rest. For instance, if the digit "1" is dialed, the projecting finger is timed to contact with the switch 145 immediately after the impulse takes place or just before the finger plate comes to rest. The 65 projecting finger is designed to forcibly contact with the stud of the switch, similarly as shown in Fig. 1 by the pawl 22, wherein the swinging tongue 215 of the finger is resiliently held forward by the spring 216 and is made to freely pass 70 the stud on the switch in dialing a number and to forcibly engage the stud in the reverse motion of the dial, when the solenoid 146 is momentarily energized.

The circuit may be traced from the negative 75

side of the source 150, by conductor 150' leading to the brush 95, thence through sleeve 94 to brush 126, conductor 151 to the switch 145, and from the switch by conductor 147, switch 148, thence by conductor 147' to the solenoid 146 and returning to the positive side of source by conductor 149. Describing the punch-print mechanism in detail: Fig. 5 from the base 157 raises the standard 158 to support the top plate 159. Adjacent to the standard is the solenoid 146, which is provided with the armature 161, having the projecting pin 162 and terminating in a forked end 163 in which the arm 164 is loosely saddled under the cross pin 165. The arm is pivoted as at point 166, between two supports 167, forming a part of the upper bar 168. Journalled in the bar and actuated by the arm is the spring depressed plunger 169, which is designed to fit in the hole 170, in the cross plate 171, connecting the bars 175 and 176, to complete the punching unit. Beneath the bar 168 equally spaced, are the symbols 172. The rear end of the bar joins the two strips 173 and 174 which lead up from the bars 175 and 176. In the outer edges of the bars are the grooves 177; the tongues 178, slidably fitting therein, constitute a portion of the top plate, forming the edge of the slot 179.

Beneath the bar 176 at the far outer end, are the ratchet teeth 180. They are spaced apart equally and coincidentally with the centers of the symbols 172 and the printed spaces 181 on the strip of paper 182. Loosely mounted on the cross-pin 183 fixed in the forked end of the armature 184, is the trigger 185, and enveloping each side is the loosely mounted forked end of the pawl 186 which is pressed against the ratchet teeth by the spring 187. The pawl has the depending arm 188, and when forced downward out of engagement with the ratchet teeth 40 by the trigger 185 also releases the detent 189, causing the punching assembly, through the two spiral springs 189', held fast at one end by the pin 190, while the other end is fastened to the end of the bars, to return to its normal position.

45 In this manner the bars are normally held backward with respect to the printing and punching line by a distance of one step-up. The drawings show however that the digit "1" has been dialed and that the magnet 152 had advanced the punching assembly by one step.

50 The advancing operation which occurs as impulses are received from the dialing mechanism is accomplished by the intermittent energization of magnet 152, and each time, the armature 184 is actuated to advance the punch print unit one notch of the ratchet bar 176, which is retained by the detent 189. After each such impulse the spring 184' returns the armature to position ready for the next impulse, this continues until 60 the digit dialed has been completely registered.

With reference to Fig. 5, when energized the solenoid 146, in drawing its armature downward against the pressure of the spring 146' and the air pressure through the control valve 146'' contacts, through the projecting pin 162, against the forked end 191' of the lever 191, which is rockably supported on the standard 192 for the purpose, when actuated, of imparting a quick upward movement to the rod 193 journalled in the bearing 192' as the forked end 191'' strikes the pin 194 of the rod. The rod carries the head 195 and is shaped to make an impression on the strip of paper or card 182 of the type or symbol carried by the bar 171. An instant later, after 75 the impression has been made, the forked end

191 lifts the rear portion of the trigger 185 to trip the pawl 186 and through the depending arm 188 also trips the detent 189. Simultaneously with this movement, the rod 196, carrying the spring pawl 189 and bearing in the top 5 plate and resiliently held downward by the spring 197, is forced upward, idly, by the lever to a distance or turn of one and one-fourth tooth of the ratchet.

The bars having been released by the pawl and 10 detent, the spiral springs 189' restores them to their normal position and as the lever 191 drops, the spring 197 expands and causes the rod 196, carrying the pawl 189, to draw the ratchet 188 around by one step-up motion, which, in being 15 fixed to the shaft 200, also imparts a like motion to the ribbon drum 201 and the two driving discs 202 and 203—the whole is supported by the standards 204.

In this way the ribbon 206 is successively 20 moved forward beneath the guide rollers 205, to present a fresh portion of the ribbon 206 for printing the symbols on the paper strip or card, and at the same time to impart one step-up motion to the strip or card along the guide ways 25 207 on the table. The two discs 208 suitably journalled beneath the table top engage the under part of the paper strip or card directly opposite to the discs 202 and 203. The discs 209, 210, and their counter discs beneath the top 30 plate, are of similar construction and design as shown by the numerals 208'.

In practice the customer's credit card, having punched holes therein, representing the number of their credit account, is introduced into 35 the holder 61 and clip 331. The card also shows, in printed form, a corresponding number, and in the lower right-hand corner the signature of the customer. The card may also show certain other signatures designated to sign for credit on 40 the back of the card. The sales person, on noting the signature and printed number, adapts the second hole in the finger plate 40', identifying the number "2", and turns it around until the movable stop 40, controlling the switch 39, 45 arrests the stroke of the finger. At this moment the solenoid 7 acts and causes the digit "2" to be printed on the face of the voucher 11'. As the movement of the contact ball is synchronously meshed with the movement of the finger plate, 50 the ball at the same time is drawn downward and momentarily stops in the second hole in the card. At this instant the magnet 65 releases the pawl 78 and permits the finger plate, under tension of the spring 85, and controlled by the 55 governor 211, for timing the impulses, to return to zero. The impulses are transmitted to the two-motion switches from the terminals 217 and 218 and register in the usual manner. The magnet 152 of the card puncher being multiply connected with the main conductors also receives the two impulses which causes the puncher assembly to move to the second position on the card. Thus energized, the two-motion switches hold their position, as does the puncher assembly, until the tripping circuit, controlling the solenoid 146, is completed momentarily by the switch 145, just previous to the stoppage of the finger plate or immediately after the last impulse. This action, before being released by the 70 step-up pawl and detent, punches a hole in the card representing the second position, and simultaneously prints the digit "2" on the upper margin of the card, designated by the numeral 212. This action also moves the ribbon and card along 75

the top plate by one step-up motion for a succeeding dialing, which in this case would be the digit "4", with the same results, until the selector, having been motivated to the last digit, 5 selects the customer's number or resistance coil on the record board and partly forms the signal circuit which the operator completes by pressing the button 100. Simultaneously with this action, the lamp 98, or 98 and 99 together, flares 10 up according to the condition of the record board; one lamp denoting approval; two lamps denoting disapproval of the credit account. The button 100 released the sales person, if desired, then proceeds to dial for a printed voucher of the 15 sale transaction, which may have a number of columns representing "Date", "Clerk", "Mdse.", "Amount", or other representations.

Should an error occur in the dialing of a number and the number be less in value than the one intended, the saleslady need only to 20 turn the finger plate around until the ball electrically contacts in the hole in the card when the whole will register and right itself. If the value be greater than the number intended the 25 button 90 must be pressed, when, without disturbing the circuit arrangement, the whole will right itself for another trial. The first four numbers dial the credit number which in being carried through the two-motion switch, finally selects the resistance coil or number on the record 30 board, and thereby conditions the dialing circuit for a return answer. - The rack bar 28 with the insulation strip 28" serves to break the circuit through two-motion switches after the credit 35 number has been dialed by the insulation strip riding under the brush 28''' and thereafter continues to hold only that part of the circuit leading through the puncher mechanism, in order to produce a facsimile record of the dial printed 40 voucher in the form of a punched card of the sale. In this way both the voucher and the card will have the same record of the sale, which may also include "returns", "exchanges" and "warehouse receipts". The punched cards may later 45 become a part of a tabulating system for striking a balance. While the drawings show how the two-motion switches and the record board may be actuated during the time when the switch 28''' electrically contacts with the metallic portion 50 of the bar 28 of the dialing mechanism, and later, to become inoperative when the switch 28''' rides over the insulation 28'', leaving, as it does, the punching unit 152-146 to register; still, the punching unit, too, may also be made inoperative 55 by opening the switch 148, or switches 148 and 154, when only the credit number is to be dialed and the printed voucher, alone, is wanted in the sending station. Any suitable means, not shown, may be employed to hold the latch 140 away from the 60 recess 141 during such period.

Many dialing units, in turn, may successively control a small number of two-motion switches. I accomplish this by a specially designed electrical circuit and a button control, which, in 65 adapting any one of the units for dialing a credit number, renders all other units inoperative as shown.

Having thus described the invention, what is claimed is:

70 1. In an apparatus of the character described, a central station, a sending station, means at the sending station for making a record of a transaction, including means for transmitting from the sending station to the central station 75 impulses constituting a message relating to the

transaction, automatically operable means at the central station responsive to the impulses for determining the advisability of completing the transaction, means for transmitting a signal regarding the transaction from the central station to the sending station controlled by the last mentioned means, and means whereby the recording means is automatically disconnected from the central station after a predetermined series of impulses have been transmitted. 5

2. In an apparatus of the character described, a central station, a sending station, means at the sending station for making a record of a contemplated transaction, means for transmitting electrical impulses from the sending station to the central station, automatically operable means at the central station responsive to said impulses for determining the advisability of completing the transaction, means controlled by the last mentioned means for indicating at the sending station approval or disapproval of the transaction, and means at the central station for making a record of the transaction. 10 15

3. In an apparatus of the character described, a central station, a plurality of sending stations, means at each sending station for temporarily rendering all other stations inoperative during operation of a selected sending station, means at a sending station for transmitting electrical impulses to the central station, means at the sending station for positively insuring the sending of correct impulses, automatically operable selective means at the central station responsive to received impulses for completing a signaling circuit, and a signal in the signaling circuit energized when the circuit is completed. 20 25 30 35

4. In an apparatus of the character described, a central station, a sending station, means at the sending station for making a record of a transaction, the recording means having electrically energized operating means and a circuit therefore including a switch, a rotary setting member, a stop for limiting turning of the setting member in one direction and effecting closing of the switch, a credit card holder, a slidable bar shifted by turning of said setting member, a latch for said bar, electrically energized releasing means for said latch having a circuit including the card holder and a feeler carried by said bar and adapted to engage the card holder through openings formed in a credit card, a signal at the sending station, a circuit for said signal having therein adjustable resistances and selector means at the central station and means at the sending station for transmitting electrical impulses to the selector means during retrograde rotation of the setting means to a normal position, and recording means at the central station having electrically energized actuating means and a circuit therefore including a switch adapted to be closed as the setting means rotates towards its normal position. 40 45 50 55 60

5. In an apparatus of the character described, a central station, a sending station, a credit card holder at the sending station, a voucher holder, means for imprinting symbols upon a voucher, electrically energized actuating means for said imprinting means having a circuit including a switch, an arm movable across the credit card holder, means for releasably holding the arm in a set position having an electrically energized releasing means included in the first circuit, a credit board at the central station including a plurality of identified resistances, a two-motion switch including a selector provided with leads 70 75

- extending to the resistances and another lead releasably connected with selected ends of the resistances, a circuit for said two-motion switch including a switch at the sending station actuated during movement of the arm for transmitting impulses to the two-motion switch and actuating the selector, and signal means at the sending station energized in accordance with the condition of a resistance selected by said selector.
6. In an apparatus of the character described, a sending station, a central station, a credit card holder at the sending station, a voucher holder at the sending station, means for imprinting symbols upon a voucher carried by the voucher holder, electrically energized actuating means for said imprinting means including a switch, setting means for said imprinting means having means associated therewith for closing the switch, a two-motion switch at the central station, means associated with the setting means for transmitting impulses to the two-motion switch and setting the selector thereof, a credit board having resistances associated with the selector and means for selectively rendering the resistances effective, signaling means in the circuit, and means at the sending station for closing the circuit through the signaling means after a resistance of the credit board has been selected.
7. In an apparatus of the character described, a central station, a sending station, a credit board at the central station including resistances having sockets at their ends, a two-motion switch at the central station including a selector provided with leads each connected with one end of a companion resistance and a return lead having branches each removably engageable in a socket at a selected end of a companion resistance, a circuit for said two-motion switch, means at the sending station for making a record of a transaction and transmitting impulses to the two-motion switch for energizing the selector thereof and effecting selection of a resistance, high and low resistance signals in the circuit adapted to be energized according to the position of a branch of the return lead related to a selected resistance of the credit board, and means for closing the circuit after a resistance has been selected and energizing one or both of said signals.
8. In an apparatus of the character described, a central station, a sending station, a plurality of identified resistances at the central station, means at the central station for selecting a predetermined resistance, a circuit for the said means including a switch at the sending station, a rotatable setting member at the sending station, means at the sending station for making a record of a transaction having electrically energized operating means and a circuit therefore including a switch adapted to be momentarily closed when the rotary setting means is turned in one direction, means for intermittently effecting closing and opening of the first switch during return rotation of the setting means to its normal position and transmitting a predetermined number of electrical impulses to the selecting means of the central station, recording means at the central station having electrically energized actuating means including a switch at the sending station adapted to be closed as the setting member approaches its normal position during return rotation, and a signal at the sending station operatively associated with the resistances and adapted to be energized in accordance with the condition of a selected resistance.
9. In an apparatus of the character described, a central station including a board having a plurality of resistances carried thereby and sockets at ends of the resistances, a two-motion switch having a selector associated therewith and provided with leads each extending to one end of a companion resistance and another lead having branches, each branch being adapted to be engaged in a socket at a selected end of a companion resistance by means to selectively render the resistance active or inactive.
10. In an apparatus of the character described, a central station including a board having a plurality of resistances carried thereby, a two-motion switch having a selector operatively associated therewith, leads extending from the selector and each engaged with a companion resistance, and another lead extending from the selector and having a plurality of branches corresponding in number to the resistances and means whereby each branch is adapted to be detachably engaged with a selected end of a companion resistance whereby the resistances may be at will rendered active or inactive.
11. In an apparatus of the character described, a sending station comprising a housing, means for holding a record sheet, a casing over said housing for overlying the record sheet, imprinting means carried by said casing, means for setting said imprinting means, an anvil for pressing the record sheet upwardly against said imprinting means, electrically energized means for shifting the anvil upwardly, and setting means for said imprinting means having means associated therewith for controlling movements of the record holding means.
12. In an apparatus of the character described, a sending station comprising means for holding a record sheet, imprinting means, a rotary shaft mounting said imprinting means over a record sheet, a dial for imparting predetermined rotary movement to said shaft and the imprinting means, an anvil movable under a record sheet towards and away from said imprinting means, an escapement for controlling movements of the record sheet holder, electrically energized means for actuating the anvil and the escapement having a circuit including a switch, and a stop for limiting turning of said dial constituting means for closing the switch.
13. In an apparatus of the character described, a sending station comprising a record sheet holder shiftably mounted and urged in one direction, an escapement for controlling movements of said holder, an anvil, a lever for moving said anvil, a solenoid having a core adapted to actuate the anvil and the escapement, a circuit for said solenoid including a normally open switch, a die carrier movable over the anvil, and setting means for said die carrier having means associated therewith for closing the switch when the die holder is moved to a set position.
14. In an apparatus of the character described, a sending station comprising a record sheet holder shiftably mounted and urged in one direction, an escapement for controlling movements of said holder, an anvil, operating means for the anvil and the escapement including a solenoid and a switch for closing a circuit for the solenoid, a credit card holder constituting a stationary contact in the circuit for the solenoid, a feeler for engaging the card holder through an opening in a card, a rack bar carrying said feeler

included in the circuit, imprinting means including a rotatable shaft and die holder carried by the shaft and extending over the anvil, a dial for turning said shaft in one direction, a stop for limiting movement of said dial in the said direction constituting means for closing said switch, means for shifting the rack bar longitudinally when said shaft is turned, a latch for releasably holding the rack bar in a shifted position, and 10 means for moving the latch to a releasing position including an electro-magnet in the circuit and an armature for the magnet.

15. In an apparatus of the character described, a sending station comprising a record sheet holder shiftably mounted and urged in one direction, an escapement for controlling movements of said holder, an anvil, operating means for the anvil and said escapement including a solenoid and a circuit therefore having a normally open switch, a rotary shaft, a die holder carried by said shaft and extending over the anvil, ribbon holding spools and a ribbon carried thereby with a portion extending between the die holder and the anvil, means actuated during rotation of said shaft for actuating the ribbon holding spools, a dial, a finger ring carried by said shaft over said dial, a stop for limiting turning of the finger ring in one direction movably mounted and adapted to close the switch when engaged and moved by a finger, a sending switch for transmitting electrical impulses to a central station, and operating means for the sending switch actuated during return of said shaft after the finger ring is released.

30 16. In an apparatus of the character described, a holder for a credit card having perforations in predetermined locations therein, a movable voucher holder, a feeler movable across the credit card holder adapted to make contact therewith through perforations in a credit card, a latch to releasably secure the feeler in a shifted position, electrically actuated means for moving said latch to a releasing position, imprinting means for forming symbols upon a voucher, an anvil for pressing a voucher against the imprinting means, electrically actuated means for operating said anvil and controlling movements of the voucher holder, means actuated during setting of said imprinting means for energizing the last mentioned means, and means actuated during return of the imprinting means to its normal position for transmitting electrical impulses to a distant station.

50 17. In an apparatus of the character described, a table for carrying a record sheet, imprinting means shiftable across the table and having upper and lower arms, the upper arm carrying dies and the lower arm having teeth forming a rack, a punch carried by the upper arm, an operating lever for said punch, means for actuating said lever, means cooperating with the rack bar for imparting movements to the imprinting means and holding the same in a set position, means for pressing a record sheet against the set imprinting means, and means for releasing the imprinting means for returning to its normal position.

55 18. In an apparatus of the character described, a central station, a sending station, means at the sending station for carrying a voucher, means for recording upon said voucher data relating to a contemplated transaction, means for transmitting electrical impulses from the sending station to the central station, automatically operable means at the central station responsive to said impulses 70 for determining the advisability of completing

the transaction, means for indicating at the sending station approval or disapproval of the transaction, means at the sending station for rendering inoperative the impulse responsive means of the central station after the indication has been made, whereby additional data may be recorded on the voucher, and means at the central station for forming a duplicate record of the transaction.

19. In a checking system, a calling station and a central station, means at the calling station for making code impulses, a circuit for carrying the impulses to the central station, means at the calling station for positively insuring the making of the impulses in accordance with any given predetermined code, code identified return signal 15 circuits and code responsive means at the central station for selecting a return signal circuit corresponding to the given code, and signal means at the calling station for indicating the condition of the selected return signal circuit.

20. In a checking system, a plurality of calling stations and a central station, means at each calling station for making code impulses, a circuit for carrying the impulses to the central station, means at each calling station for connecting it to said circuit and simultaneously locking out each and all other calling stations, means at each calling station for positively insuring the making of the code impulses in accordance with any given predetermined code, 30 code identified return signal circuits and code responsive means at the central station for selecting a return signal circuit corresponding to the given code, and signal means at each calling station for indicating the condition of the selected return signal circuit.

35 21. In a checking system a plurality of calling stations each having impulse sending means and a central station, a main circuit from the central station, a normally open secondary circuit 40 for each calling station connected to the main circuit, locking means for each impulse sending means, means for closing each secondary circuit having means associated therewith for controlling all of said locking means.

45 22. In a checking system, a plurality of calling stations each having impulse sending means and a central station, a main circuit from the central station, a secondary circuit from each calling station connected to the main circuit, 50 locking means for each impulse sending means, means for opening and closing each secondary circuit having means associated therewith for controlling all of said locking means.

55 23. In a checking system, a plurality of calling stations each having impulse sending means and a central station, a main circuit from the central station, a secondary circuit from each calling station connected to the main circuit, locking means for each impulse sending means 60 comprising electro-magnetic means in a common auxiliary circuit, means for opening and closing each secondary circuit having means operable therewith for opening and closing said auxiliary circuit.

65 24. In a customer credit checking system, a calling station and a central station, means at the calling station for producing coded impulses in positive accordance with any given customer's code, code identified means variable in relation to the corresponding customer's credit and code responsive means for selecting the code identified means corresponding to the given customer's code and means automatically indicating at the 70 75

- calling station the condition of the code identified means selected.
25. In a credit checking and accounting system, a sending station and a central station, code impulsive and recording means at the sending station and means for limiting the operation of the impulsive and recording means to any selected predetermined multi-digit code, code identified return signal circuit means at the central station, code responsive means at the central station for selecting return signal circuit means, recording means at the central station, and trunk circuit means for transmitting code impulses from the sending station to the code responsive means and the recording means.
- 10 26. In a credit checking and accounting system, a sending station and a central station, manually operated code impulsive means at the sending station, automatic means at the central station for selecting a code identified return signal circuit, positively selective control means for the code impulsive means including a holding device adapted for automatic release when the proper code is given and for manual release in case of error.
- 15 27. In a credit checking and accounting system, a sending station and a central station, manually operated spring return coding means at the sending station, code responsive automatic means at the central station for selecting a code identified return signal circuit, trunk circuit means connecting the central and sending stations, positively selective control means for the coding means including a holding device adapted for automatic release when the proper code is given; and manual release means,
- 20 including means for disconnecting the trunk circuit, in case of error.
- 25 28. In a communication system, a sending station and a central station, manually operated spring return coding means at the sending station, circuit means between the two stations, positively selective control means at the sending station including a holding device for the coding means adapted for automatic release when the proper code is given and manual release means for the coding means, including disconnecting means for the between station circuit means, in case of error.
- 30 29. In a credit checking and accounting system, a sending station and a central station, code impulsive means and recording means at the sending station and means for limiting the impulsive and recording means to any selected predetermined series of coded digits, code identified return signal circuit means at the central station, code responsive means at the central station for selecting return signal circuit means, recording means at the central station, trunk circuit means for transmitting code impulses from the sending station to the code responsive means and the recording means at the central station, and means associated with the recording and limiting means at the sending station for automatically disconnecting the code responsive means from the trunk circuit means when the selected predetermined series of coded digits has been completed, whereby subsequently coded digits may be recorded at the central station without affecting the code responsive means.

JOHN P. BUCKLEY.
